(US)**

(57) **CLAIM**

(**) Term: **14 Years**

The ornamental design for a moulding, as shown and described.

(21) Appl. No.: **29/186,582**

DESCRIPTION

(22) Filed: **Jul. 18, 2003**

FIG. 1 is a perspective view of a moulding showing our new design;

Related U.S. Application Data

FIG. 2 is an end view thereof;

(62) Division of application No. 29/164,541, filed on Jul. 26, 2002, now Pat. No. Des. 480,483.

FIG. 3 is a front view thereof;

(51) **LOC (7) Cl. 25-01**

FIG. 4 is a bottom view thereof; and,

(52) **U.S. Cl. D25/119**

FIG. 5 is a top view thereof.

(58) **Field of Search** D25/119, 136;
52/216.1, 218, 212.03, 287.1

The fragmented lines indicate that the moulding continues indeterminately in the direction depicted. The single broken line portions are for illustrative purposes only and form no part of the claimed design.
